CLAIM

The ornamental design for a cup, as shown and described.

DESCRIPTION

FIG. 1 is a perspective view of a cup showing the claimed design;

FIG. 2 is a front view of the cup as shown in FIG. 1;

FIG. 3 is a back view of the cup as shown in FIG. 1;

FIG. 4 is a left-side view of the cup as shown in FIG. 1;

FIG. 5 is a right-side view of the cup as shown in FIG. 1;

FIG. 6 is a top view of the cup as shown in FIG. 1; and,

FIG. 7 is a bottom view of the cup as shown in FIG. 1.

The broken lines in the drawings depict portions of the cup that form no part of the claimed design.
